UNITED STATES PATENT-OFFICE.

JAMES P. SNEDDON, OF BAYONNE, NEW JERSEY, ASSIGNOR TO THE BABCOCK & WILCOX COMPANY, OF BAYONNE, NEW JERSEY, A CORPORATION OF NEW JERSEY.

WATER-TUBE BOILER.

1,321,566.

Specification of Letters Patent. Patented Nov. 11, 1919.

Application filed December 10, 1915. Serial No. 66,061.

To all whom it may concern:

Be it known that I, JAMES P. SNEDDON, a citizen of the United States, residing at Bayonne, in the county of Hudson and State 5 of New Jersey, have invented a new and useful Improvement in Water-Tube Boilers, of which the following is a full, clear, and exact description, reference being had to the accompanying drawings, forming part of 10 this specification, in which—

Figure 1 is a sectional side elevation of one form of boiler constructed in accordance with my invention; Fig. 2 a detail showing the auxiliary drum support of Fig. 15 1; Fig. 3 a view similar to Fig. 1 showing another form of the invention; Fig. 4 a detail view showing the auxiliary drum mounting of Fig. 3; and Figs. 5 and 6 partial cross sections showing slight modifications. Similar reference numerals indicate 20 similar parts in the several views.

My invention relates to the general type of Stirling boilers, wherein upper transverse steam and water drums are connected by 25 banks of tubes to a lower mud drum or drums, the gases being directed by baffling in serial passes over the banks.

The object of the invention is to prevent or reduce "priming." When the water fed 30 to a boiler contains a considerable amount of foreign matter, such as earthy salts and other chemical constituents, the concentration of these salts and elements in the boiler will rise to a point where the water will 35 foam on being evaporated. Unless special provision is made to allow the foam to separate out from the steam, it will be carried over with the steam, giving what is known as a "priming" action.

Referring to Figs. 1 and 2; the numerals 40 2^a, 3^a and 4^a represent the front, middle and rear transverse steam and water drums of a Stirling boiler. These drums are connected by banks of tubes 5^a, 6^a and 7^a with a transverse mud drum 8^a. Baffling shown at 9^a, 45 10^a and 11^a is arranged to direct the gases rising from the furnace 12^a in serial passes over the banks to the offtake 13^a. 14^a designates water circulators connecting the 50 water spaces of the drums 2^a and 3^a. The drums 3^a and 4^a are also preferably connected by water circulators 17^a, both sets of water circulators supporting tiling, as shown.

55 The steam in the front drum 2^a is taken

through the steam circulators 33 to the middle drum 3^a, and from the latter to the rear drum 4^a through steam circulators 34. From the rear drum the steam passes through pipes 35 into a supplemental steam drum 19^a 60 which is preferably mounted above and parallel with the middle drum 3^a. The supplemental drum is cut off from the steam space of the middle drum 3^a by plates 32, bolted, as shown in Fig. 2. 65

In this form of my invention the steam generated in the front drum, which contains a certain amount of foam, will pass over through the pipes 33 into the middle drum 3^a, which serves as a settling chamber. 70 From the drum 3^a, the steam, from which most of the moisture has been eliminated, passes over into the rear drum 4^a and thence into the supplemental drum 19^a in which the steam is completely separated from any 75 foam or priming water and passes out as dry steam through the perforations in the dry plate 20^a. The dry plate not only assists in separating the foam from the steam but also serves to minimize the effect of any 80 sudden demand of steam from the boiler which would cause a sudden corresponding reduction of pressure in the boiler tending to aggravate the priming action. The water collecting in the dry plate flows 85 through pipe 30 to the bottom of the drum 19^a and is led off therefrom through the pipe 36 to the mud drum 8^a.

In Fig. 3 I show another arrangement with a boiler substantially the same as that 90 shown in Fig. 1, the same parts being indicated by the same reference numbers with the exponent "b" applied thereto. In this form I use a dry plate 20^b similar to the dry plate 20^a of Fig. 1. Instead, however, of 95 draining the water from the supplemental drum to the mud drum, I lead such water through pipe 37 directly into the water space of the middle steam and water drum 3^b. As shown in Fig. 4 a perforated plate 100 32^b across the opening in the drum 19^b permits the water to collect in the nipple connection between said drum and the drum 3^b and to escape through the pipe 37. Also, in this form, I show a splash plate 38 in the 105 supplemental drum between the line of steam circulators 35^b and the dry plate 20^b.

Instead of leading the dry steam direct from the supplemental drum 19^a, as in Fig. 1, it may be led through the main 21^b to a 110

superheater 22^b located, as shown, in the second pass of the boiler.

In Figs. 5 and 6 I have shown a dry pipe 31^b instead of the dry plate 20^b of Fig. 3.

- 5 In Fig. 5 the water collecting in the supplemental drum is drawn off through the pipe 36 and discharged into the mud drum 8^a as shown in Fig. 1. In Fig. 6 the water collecting in the supplemental drum is discharged through the pipe 37 into the middle steam and water drum as in Fig. 3.

The supplemental drum is preferably supported on the intermediate steam and water drum, which, in turn, is supported with the 15 boiler on the structural work of the setting. The advantage of my invention results from the use of this supplemental drum in a boiler of the type illustrated, such use greatly reducing or preventing priming.

- 20 As described, the drain pipe from the supplemental drum leads to a point below the water level either in the mud drum or the middle steam and water drum. This water seal prevents short circuiting of the 25 steam back through the drain pipe. Should the lower end of the drain pipe not be sealed, steam would flow back through it into the supplemental drum and thus prevent the flow of water from the supplemental 30 drum and prevent proper draining of the latter.

What I claim and desire to secure by Letters Patent of the United States is:—

1. A steam boiler having three upper 35 transverse drums connected by banks of tubes to a mud drum or drums, steam circulators connecting the middle and rear upper drums and arranged to conduct the steam to the rear drum, an independent supplemental 40 drum and continuously open connections to lead the steam thereto from the rear

drum, a steam drying device in the outlet of said supplemental drum, and a continuously open drain pipe from said supplemental drum leading to a point below the water 45 level in the boiler.

2. A steam boiler having three upper transverse drums connected by banks of tubes to a mud drum or drums, steam circulators connecting the middle and rear steam 50 and water drums and arranged to conduct the steam to the rear drum, an independent supplemental drum and continuously open connections to lead the steam thereto from the rear drum, a steam drying device in the 55 outlet of said supplemental drum, and a continuously open drain pipe from said supplemental drum to a steam and water drum and discharging below the water level therein.

3. A steam boiler having three upper transverse drums connected by banks of tubes to a mud drum or drums, steam circulators connecting the middle and rear steam 60 and water drums and arranged to conduct the steam to the rear drum, an independent supplemental drum and continuously open connections to lead the steam thereto from the rear drum, a steam outlet from said supplemental drum, and a continuously open 70 drain pipe from said supplemental drum to a steam and water drum, said drain pipe discharging below the water level in the drum.

In testimony whereof I have hereunto 75 signed my name in the presence of two subscribing witnesses.

JAMES P. SNEDDON.
